US0D1030978S

(12) **United States Design Patent** (10) Patent No.: **US D1,030,978 S**
(45) Date of Patent: ** Jun. 11, 2024

(54) **VALVE ACTUATOR**

(71) Applicant: **AUMA Riester GmbH & Co. KG**,
Müllheim (DE)

(72) Inventor: **Rudolf Morlang**,
Villingen-Schwenningen (DE)

(**) Term: **15 Years**

(21) Appl. No.: **35/517,587**

(22) Filed: **Jun. 6, 2023**

(80) **Hague Agreement Data**

Int. Filing Date: **Jun. 6, 2023**

Int. Reg. No.: **DM/229611**

Int. Reg. Date: **Jun. 6, 2023**

Int. Reg. Pub. Date: **Jun. 23, 2023**

(51) **LOC (14) Cl.** 23-01

(52) **U.S. Cl.**

USPC **D23/249**

(57) **CLAIM**

The ornamental design for valve actuator, as shown and described.

DESCRIPTION

1. Valve actuator

2. Valve actuator

3. Valve actuator

4. Valve actuator

5. Valve actuator

6. Valve actuator

7. Valve actuator

8. Valve actuator

1. Name of the product in which the design is embodied:
Valve actuator; 2. Intended use of the product: it is used for

regulating a valve; 3. Key design feature: shape of the product; 4. View best illustrating the key design feature: perspective view of the first design; 5. Basic design: design 1.
